ROLLING MILL INCHING DEVICE

James Rodger Shields and Eugene W. Barth, Pittsburgh, and Kenneth Wayne Fitzsimmons, Greensburg, Pa., assignors to Elliott Company, Jeannette, Pa., a corporation of Pennsylvania

Application June 15, 1955, Serial No. 515,604

15 Claims. (Cl. 74—665)

This invention relates to the driving mechanism for rolling mills, and more particularly to a mechanical inching drive, by which the spindles can be turned very slowly for roll changes.

In installing mill rolls, it is necessary to turn the drive spindles into a position where the wabblers on the ends of the spindles and rolls will match, so that the wabblers can be connected together. The main drive for the mill turns the spindles too fast for this purpose, so other means have to be provided for slowly rotating or "inching" the spindles. Heretofore, such means have been quite expensive and sometimes not very satisfactory or safe.

It is among the objects of this invention to provide a rolling mill inching drive, which is mechanical and relatively small and inexpensive, which can inch the spindles in either forward or reverse direction, which cannot be actuated while the main drive is operating, and which includes means for preventing operation of the main drive while the inching mechanism is operating.

In accordance with this invention, a bull gear is adapted to be operatively connected with the spindles that turn the mill rolls. The spindles normally are driven by a main drive motor. A small retractable idler gear is adapted to mesh with the bull gear, but normally they are spaced apart. Means is provided, independent of the motor, for driving the idler gear slowly so that when it is meshed with the bull gear by manually controlled means, when the main drive is not operating, the spindles will be rotated very slowly. Preferably, the idler gear is driven by a drive pinion, and the former is carried by a pivotally mounted cage which swings the idler gear into and out of mesh with the bull gear. Means is provided which is actuated by the bull gear when the main drive starts, to assure separation of the two gears. When the idler gear is moved into mesh with the bull gear, the circuit to the main drive motor is opened. There also is provided means actuated by the bull gear as soon as it starts to be driven by the main drive, for making it impossible to move the idler gear against the bull gear as long as the mill is operating.

The preferred embodiment of the invention is illustrated in the accompanying drawings, in which:

Fig. 1 is a schematic plan view of a rolling mill and its drive;

Fig. 2 is a greatly enlarged side view of the inching mechanism;

Fig. 3 is a vertical section taken on the line III—III of Fig. 2;

Fig. 4 is an enlarged vertical section of the lower part of the mechanism, taken on the line IV—IV of Fig. 2;

Fig. 5 is a horizontal section of a detail taken on the line V—V of Fig. 4;

Fig. 6 is a horizontal cross section taken on the line VI—VI of Fig. 4;

Fig. 7 is an enlarged vertical section of one of the controls taken on the line VII—VII of Fig. 3; and

Fig. 8 is an electric wiring diagram.

Referring to Fig. 1 of the drawings, the vertically spaced rolls 1 of a rolling mill are driven from a pinion stand 2 through spindles 3. The pinion stand is driven by a drive shaft 4 that is rotated by reduction gearing 5, which in turn is driven by a large electric motor 6 through a pinion shaft 7. In order to change the rolls, the spindles have to be disconnected from them. When the rolls are replaced, the wabbler connections between the ends of the spindles and rolls seldom are in position to interengage with each other, so the spindles must be rotated very slowly the number of degrees necessary to permit coupling. In accordance with this invention, this inching of the spindles is done by means of a mechanism or drive 8 that operates when the main motor 6 is not operating. At such times the reduction gearing is driven slowly by the inching mechanism through an extension 9 of the reduction gearing pinion shaft 7 on the side of the gearing opposite the main motor.

As shown in Figs. 2 and 3, the inching drive includes a suitable base 11, on one end of which a gear housing 12 is mounted. In the upper part of this housing a large bull gear 13 is mounted on the end of shaft extension 9. While the inching mechanism is not operating, the bull gear serves no purpose but is driven like a flywheel by shaft 9 at normal main motor speed. The bull gear can perform its intended function only when the main motor is not operating. At such times the spindles can be turned over very slowly by driving them from the bull gear through shaft 9 and the reduction gearing. For this purpose the bull gear can be driven slowly in either direction by a small, reversible gear motor 14 mounted on the base of the mechanism at one side of housing 12.

Journalized in the lower part of housing 12 is a shaft 16 that is driven by the gear motor. Integral with this shaft is a drive pinion 17 that meshes with two small idler gears 18 and 19 located between it and the lower part of the bull gear, as shown in Fig. 4. Idler gear 18 is journaled in the upper part of an inclined cage 21, the lower part of which straddles pinion 17 and is rockably mounted on pinion shaft 16. The other idler gear 19 is mounted in a similar cage 22 extending at an angle of a little more than 90° to the first cage and having its lower end also pivotally mounted on the pinion shaft independently of the other cage. The lower parts of the two cages are staggered on the shaft as shown in Fig. 6. The upper sides of the cages are open so that they can extend into each other and to enable the two gears to mesh with the bull gear when desired. Normally both cages are in their lower position, where they rest on screws 23 mounted in the upper walls 24 of open-end chambers in the lower part of the housing.

Projecting from the upper ends of the cages are lugs 26 and 27 provided with holes, through which studs 28 and 29 extend. The lower ends of the studs are secured in bosses 31 below the upper walls 24 of the underlying chambers. Compressed between lug 26 and the adjacent boss is a coil spring 32 which takes the weight of cage 21 and its gear, but which is not strong enough to lift the cage by itself. A similar but weaker spring 33 is compressed between lug 27 and a sleeve 34 on stud 29.

Extending downward from the lower ends of the cages are arms 36 provided at their lower ends with slots that receive pins 37 on the outer ends of a pair of rods 38. These rods are slidably mounted in the chamber end walls 39 and extend back into solenoid coils 41 and 42 where they are connected to the cores of the coils. When a coil is energized, by the closing of a manually actuated switch 43 (Fig. 8), the coil pulls the adjacent arm 36 toward it and thereby, with the help of the coil spring 33 above it, swings the adjoining cage upward to mesh the idler gear with the bull gear. Once an idler starts to mesh with the bull gear, the forces on the idler gear are

such that a natural moment arises which holds its cage in position as long as pinion 17 drives the idler. The gear motor then drives the bull gear and, because of the reduction through the bull gear and the mill-drive gearing, the spindles are driven at a very slow speed for inching them. For example, in one installation pinion 17 is driven at 28 R. P. M. and drives the bull gear at about 6 R. P. M. By the time the speed is reduced further through reduction gearing 5, the spindle speed is only about $\frac{1}{4}$ R. P. M.

The direction of inching depends upon the direction of rotation of the gear motor and upon the particular idler gear that is moved into engagement with the bull gear. During inching, the right-hand idler 18 in Fig. 4 is used to drive the bull gear in a counterclockwise direction, but it is driven in a clockwise direction by the other idler gear when the motor is reversed. Assuming that the direction of rotation of the bull gear during normal operation of the mill is in a clockwise direction, it will be seen that if idler gear 19 does not drop away from the bull gear after inching, the clockwise rotation of the bull gear when the main motor takes over will swing the left-hand cage down and thereby prevent the gear motor from being driven by the bull gear and ruined by the high speed main motor.

On the other hand, if inching has been in the other direction and the other idler gear 18 hangs up against the bull gear after the main motor is started, the rotation of the bull gear clockwise will tend to hold gear 18 in engagement with it. To prevent this from happening, a clutch pinion 46 is mounted in one end of a clutch cage 47, the opposite end of which is rockably mounted in a special bracket 48 in housing 12. Projecting from the bottom of the cage is a pin 49 that engages a projecting arm 50 on the adjacent gear cage 21. The clutch pinion is part of an overrunning clutch and can turn only in a clockwise direction, as viewed in Fig. 4. Therefore, as long as the bull gear is being driven counterclockwise by the gear 18, the clutch pinion will be rotated. However, as soon as the bull gear starts to be driven clockwise by the main motor 6, the clutch pinion will stop rotating and therefore the bull gear will swing that pinion and its cage downward, which will force gear 18 away from the bull gear and thereby protect the small motor.

In order to insure meshing of the clutch pinion with the bull gear when idler gear 18 is swung upward, so that the pinion cannot prevent the idler gear from meshing, steps are taken to have the rotating idler gear mesh with the bull gear and start it rotating before the latter is touched by the clutch pinion. Accordingly, bracket 48 is rockably mounted on top chamber wall 24 for moving clutch cage 47 toward and away from the bull gear in a substantially radial direction, and as the bull gear is rotating when the clutch pinion engages it, the two quickly mesh together. The base of the bracket fits over a rocker pin 52 mounted in a groove in the top of wall 24, and while the clutch pinion engages the bull gear the bracket base between the pin and the idler cage rests flat on the supporting wall as shown. At that time the bottom of the bracket base behind the rod pin is inclined upward and outward. The bracket is held in that position by a heavy coil spring 53 connecting it with arm 50 of the adjacent idler cage. When solenoid 41 is deenergized and the clutch pinion and its cage are swung down as explained in the preceding paragraph, the outer end of arm 50 will move toward bracket 48 and remove the tension from the spring. This will allow a coil spring 54 on a vertical stud 55, extending through an oversize hole in the base of the bracket and screwed into wall 24, to press the outer end of the bracket base down flat against wall 24 as the inner end of the bracket tilts up. The result is that the upper end of the bracket pulls the clutch pinion outward away from the bull gear. The ends of spring 53 are fastened to the bracket and arm 50 through slotted connections 56 that allow idler gear 18,

when solenoid 41 is energized, to start to mesh with and drive the bull gear before the spring begins to rock bracket 48 toward the bull gear. The bracket is held in position on the rock pin by front and rear studs 57 and 58 extending loosely through holes in the bracket base and screwed into wall 24. The heads of these studs are spaced far enough from the wall to allow for the rocking movement of the bracket.

Another safety feature is that when a solenoid rod 38 is pulled into a coil, a lateral projection 61 (Fig. 5) on the rod opens a normally closed electric switch 62 which opens the electric circuit to the main motor 6, so that it is impossible to start that motor during inching.

Of course, it is important that the inching mechanism 15 solenoids 41 and 42 not be energized accidentally while the main motor is operating. To make certain that such an accident will not occur, the circuit of gear motor 14 contains a normally closed, fluid-pressure operated electric switch which is opened automatically as soon as the 20 main motor 6 starts to operate. This switch 66, shown in Fig. 3, is opened by the pressure of a head of oil in a standpipe 67 (Fig. 7) inside of a tank 68 supported by the upper part of gear housing 12. The lower end of the standpipe is in communication with a hydraulic pump 69 submerged in oil and driven through a short shaft 71 from the center of the bull gear. The lower part of the standpipe also is connected through a pipe 72 with the switch 66, so that as soon as the level of the oil in the standpipe is high enough the weight of the oil will exert 30 enough pressure to open the switch. The oil overflows the top of the standpipe and is recirculated. Part way down the side of the standpipe there is a small orifice 73, which permits the oil above it to leak out of the pipe when the pump stops. Consequently, a short time after 35 the pump stops, the level of oil in the pipe falls far enough to permit the switch to close so that the inching mechanism can be operated.

The arrangement is such that enough oil will be pumped 40 into the standpipe within three seconds after the main motor starts to drive the bull gear to open switch 66. The switch will remain open until after the motor has stopped. During deceleration of the bull gear, the standpipe will remain full of oil until the bull gear speed has decreased to about 15 R. P. M., at which time the flow 45 through orifice 73 equals the pump discharge. From there to zero R. P. M. the head of oil will fall, due to draining out through the orifice, but at a varying rate depending on the rate of deceleration. The time delay thus incorporated in this safety system should be 20 or 50 25 seconds, which means that the switch should not close until the motor has stopped, or perhaps 15 seconds or so later. This can be controlled by the size of orifice 73.

According to the provisions of the patent statutes, we 55 have explained the principle of our invention and have illustrated and described what we now consider to represent its best embodiment. However, we desire to have it understood that, within the scope of the appended claims, the invention may be practiced otherwise than as specifically illustrated and described.

60 We claim:

1. In a rolling mill having roll-driving spindles normally driven by a main drive, a mechanical inching drive for the spindles comprising a bull gear operatively connected with the spindles and normally driven by said main drive, a small retractable idler gear adapted to mesh with the bull gear but normally spaced from it, means independent of said main drive for driving the idler gear slowly, and manually controlled means for meshing the idler gear with the bull gear when said main drive 65 is inoperative, whereby to permit the spindles to be rotated slowly by said independent drive means while rolls are being installed in the mill.

2. An inching drive as defined in claim 1, including 70 means for swinging the idler gear away from the bull gear and operated by rotation of the bull gear when said main

drive starts, to assure separation of the idler gear from the bull gear.

3. An inching drive as defined in claim 1, including means actuated by said manually controlled means adapted to render the main drive inoperative as long as the idler and bull gears are in mesh.

4. An inching drive as defined in claim 1, including means actuated by the bull gear, as soon as the main drive starts driving the bull gear, for making it impossible to operate said manually controlled means as long as the main drive is operating.

5. Rolling mill apparatus comprising roll-driving spindles, a shaft operatively connected with the spindles for driving them, a prime mover for normally driving the shaft, a bull gear operatively connected with the shaft and normally driven thereby, a small retractable idler gear adapted to mesh with the bull gear but normally spaced from it, means independent of said prime mover for driving the idler gear slowly, and manually controlled means for meshing the idler gear with the bull gear when said prime mover is not operating, whereby to permit the shaft to be driven slowly by said independent drive means while rolls are being installed in the mill.

6. In a rolling mill having roll-driving spindles normally driven by a main drive, a mechanical inching drive for the spindles comprising a bull gear operatively connected with the spindles and normally driven by said main drive, a small idler gear adapted to mesh with the bull gear but normally spaced from it, a drive pinion meshing with the idler gear, a cage carrying the idler gear and rockable around the axis of the pinion, means independent of said main drive for driving the pinion slowly, and manually controlled means for swinging the cage toward the bull gear to move the idler gear into mesh with it when said drive is not operating, whereby to permit the spindles to be rotated slowly by said independent drive means while rolls are being installed in the mill.

7. In a rolling mill having roll-driving spindles normally driven by a main drive, a mechanical inching drive for the spindles comprising a bull gear operatively connected with the spindles and normally driven by said main drive, a small idler gear adapted to mesh with the bull gear but normally spaced from it, a drive pinion meshing with the idler gear, a cage carrying the idler gear and rockable around the axis of the pinion, means independent of said main drive for driving the pinion slowly, and electromagnetic means operatively connected with said cage for swinging it toward the bull gear to mesh the idler gear with the bull gear when said main drive is not operating, whereby to permit the spindles to be rotated by said independent drive means while rolls are being installed in the mill.

8. An inching drive as defined in claim 6, including a pinion rotatable only one way and normally spaced from the bull gear, and means actuated by said cage for moving said one-way pinion into mesh with the bull gear when the cage is swung toward it, the one-way pinion being rotatable by the bull gear only when the latter is driven by said idler gear, whereby reversal of the bull gear will cause said cage-actuated means to swing the cage and idler gear away from the bull gear.

9. A mechanical inching drive for the spindles of a rolling mill normally operated by a main drive, said inching drive comprising a bull gear adapted to be operatively connected with the spindles, a drive pinion below the center of the bull gear and spaced therefrom, a pair of cages having inner ends independently rockable around the axis of the pinion and extending laterally therefrom in opposite directions, a small idler gear journaled in the outer end of each cage and meshing with the pinion, said cages normally holding said idler gears spaced from the bull gear, selective means for swinging either cage upward to mesh its idler gear with the bull gear when said main drive is not operating, and a reversible motor for

driving said pinion to cause said last-mentioned idler gear to drive the bull gear.

10. A mechanical inching drive for the spindles of a rolling mill normally operated by a main drive, said inching drive comprising a bull gear adapted to be operatively connected with the spindles, a small retractable idler gear adapted to mesh with the bull gear but normally spaced from it, an electric motor, means operatively connecting said motor with the idler gear for driving the idler gear slowly, manually controlled means for meshing the idler gear with the bull gear when said main drive is inoperative, an electric switch in the motor circuit, and means responsive to the speed of the bull gear for operating the switch automatically when the bull gear is driven at a predetermined speed by the main drive for opening the circuit to said motor.

11. A mechanical inching drive for the spindles of a rolling mill normally operated by a main drive, said inching drive comprising a bull gear adapted to be operatively connected with the spindles, a small retractable idler gear adapted to mesh with the bull gear but normally spaced from it, an electric motor, means operatively connecting said motor with the idler gear for driving the idler gear slowly, manually controlled means for meshing the idler gear with the bull gear when said main drive is inoperative, a normally closed switch in the circuit of said motor, and fluid pressure means that is operated when the bull gear is driven by the main drive for opening said switch.

12. A mechanical inching drive for the spindles of a rolling mill normally operated by a main drive, said inching drive comprising a bull gear adapted to be operatively connected with the spindles, a small retractable idler gear adapted to mesh with the bull gear but normally spaced from it, an electric motor, means operatively connecting said motor with the idler gear for driving the idler gear slowly, manually controlled means for meshing the idler gear with the bull gear when said main drive is inoperative, a normally closed switch in the circuit of said motor, a standpipe provided with a side drain orifice, a conduit connecting the bottom of the standpipe with said switch, and a pump operated by the bull gear for pumping liquid up into the standpipe and past said orifice when the bull gear is driven rapidly by said main drive, the head of liquid in the standpipe being adapted to open said switch.

13. A mechanical inching drive for the spindles of a rolling mill normally operated by a main drive, said inching drive comprising a bull gear adapted to be operatively connected with the spindles, a small idler gear adapted to mesh with the bull gear but normally spaced from it, a drive pinion meshing with the idler gear, a cage carrying the idler gear and rockable around the axis of the pinion, means independent of said main drive for driving the pinion slowly, manually controlled means for swinging the cage toward the bull gear to move the idler gear into mesh with it when said main drive is not operating, an electric switch controlling the operation of the main drive, and means operating the switch when the cage is swung toward the bull gear for rendering the main drive inoperative.

14. A mechanical inching drive for the spindles of a rolling mill normally operated by a main drive, said inching drive comprising a bull gear adapted to be operatively connected with the spindles, a small idler gear adapted to mesh with the bull gear but normally spaced from it, a drive pinion meshing with the idler gear, a cage carrying the idler gear and rockable around the axis of the pinion, means independent of said main drive for driving the pinion slowly, electromagnetic means operatively connected with said cage for swinging it toward the bull gear to mesh the idler gear with the bull gear when said main drive is not operating, and an electric switch controlling the operation of the main drive and operated by the cage-swinging movement of said electromagnetic

means for rendering the main drive inoperative as long as the idler gear is meshing with the bull gear.

15. A mechanical inching drive for the spindles of a rolling mill normally operated by a main drive, said inching drive comprising a bull gear adapted to be operatively connected with the spindles and to be driven by the main drive in one direction, a drive pinion below the center of the bull gear and spaced therefrom, a pair of cages having inner ends independently rockable around the axis of the pinion and extending laterally therefrom in opposite directions, a small idler gear journaled in the outer end of each cage and meshing with the pinion, said cages normally holding said idler gears spaced from the bull gear, selective means for swinging either cage upward to mesh its idler gear with the bull gear when said main drive is not operating, a reversible motor for driving said pinion to cause said last-mentioned idler gear to drive the bull gear, a pinion rotatable only one way and normally spaced from the bull gear, means for moving said one-way pinion into mesh with the bull gear, said one-way pinion-moving means being actuated by the cage carry-

5 ing the idler gear that drives the bull gear in the direction opposite to said one direction, and means operatively connecting said last-mentioned cage and pinion-moving means for delaying engagement of the one-way pinion with the bull gear until after the adjacent idler gear starts to rotate the bull gear in said opposite direction, the one-way pinion being rotatable by the bull gear only while the bull gear is driven by said adjacent idler gear, whereby reversal of the bull gear by the main drive will 10 cause said one-way pinion-moving means to swing the adjoining cage and idler gear away from the bull gear.
